PROPELLER TYPE FAN

John A. Wooden, Indianapolis, Ind.

Application February 16, 1954, Serial No. 29,055

Term of patent 3½ years

(Cl. D26—7)

FIG. 2

FIG. 1

To all whom it may concern:

Be it known that I, John A. Wooden, have invented, a new, original, and ornamental Design for a Propeller Type Fan, of which the following is a specification, reference being had to the accompanying drawing, forming a part hereof.

Fig. 1 is a front elevation of a propeller type fan, showing my new design.

Fig. 2 is a side elevation thereof.

I claim:

The ornamental design for a propeller type fan, as shown.
